SHEET POSITIONING MEANS FOR
PRINTING PRESSES

Tom Keene, Detroit, Mich.

Application April 6, 1953, Serial No. 347,086

5 Claims. (Cl. 271—60)

This invention relates to gauges and more particularly to feed gauges for printing presses.

Broadly, the invention comprehends a gauge for a printing press comprising a pair of corresponding sheet positioning means of simple and durable structure and of high efficiency.

An object of the invention is to provide a simple and inexpensive sheet positioning means for printing presses operative to compensating for an inherent differential in the widths of sheets of paper of supposedly the same size.

Another object of the invention is to provide a sheet positioning means for printing presses which may be easily and quickly mounted on the feed board of a printing press and readily adjusted by finger touch movement.

A further object of the invention is to provide a sheet positioning means for printing presses which may be readily advanced or retracted and swung to a desired position.

A feature of the invention is a flat, thin metallic strip having an elongated slot and a pin per se on one end thereof supporting a shiftable sleeve.

Another feature of the invention is a sleeve having slight lateral movement in all directions.

A further feature of the invention is to provide a sheet positioning means for printing presses including a flat metal member having a pin or stud normal thereto and a sleeve loosely mounted on the pin for lateral movement in all directions.

Other objects and advantages of the invention will more fully appear from the following description when taken in connection with the accompanying drawings forming a part of this specification and in which:

Fig. 1 is a perspective view of a feed board for a printing press illustrating the sheet positioning means as mounted thereon; and

Fig. 2 is an enlarged view partly broken away, and partly in section, and illustrating the relationship of the pin and sleeve.

It is well known to those conversant in the art of printing that great difficulty is encountered in accurately feeding sheets of paper to a printing press. This is due principally to slight variations in the width of sheets of paper supposedly of the same size and a lack of suitable sheet positioning means operative to compensate for the differential in width of the sheets.

In the incident invention, a conventional feed board for printing presses indicated at A has mounted thereon a pair of corresponding sheet positioning means indicated generally at 10. Each positioning means includes a flat, narrow and relatively thin plate 12 having rounded ends 14 and 16 and an elongated slot 18. A pin or stud 20 is mounted on the end 16 of the plate in normal relation thereto and a thin washer 22 fitted on the pin is spot welded to the plate. A stout sleeve 24 supported on the pin has a larger inner diameter than that of the pin so as to provide for radial movement of the sleeve in all directions, and the sleeve is held against axial displacement as by a head 26 on the pin.

A bolt 28 having a rounded head 30 is passed through the elongated slot 18 and a suitable aperture in the feed board, and the bolt receives a thumb nut 32 for clamping the sheet positioning means on the feed board. From the foregoing, it is clear that the sheet positioning means may be adjusted by advancing or retracting or by swinging it on the stationary support or bolt 28, and that when

2

adjusted to the desired position with the washer 22 under the edge of a sheet of paper, the sleeve 24 will move in any direction in a plane transversely of and normal to the pin to compensate for inherent differential in the width of the sheets of paper in use.

The instant invention is particularly applicable to that type of printing presses known as the vertical press where-in the feed board rocks between the cylinder and the feed table which supports the stock to be printed.

When the feed board shifts from the cylinder toward the feed table, the feed board moves in an arc and as it approaches the feed table the upper or outer end of the board is inclined slightly downwardly. During this movement the sleeves 24 shift, and when the feed board is in position for the reception of a sheet of paper from the stack, the sheet is automatically fed from the stack to the feed board. As the sheet is fed from the stack to the feed board the sheet slides over the gauge and comes to rest with its rear edge on the washer 22, then as the feed board moves toward the cylinder for transfer of the sheet thereto, the sleeves bear against the rear edge of the sheet and serve to urge the sheet in position and the shiftable characteristic of the sleeve compensates for variations in the sheets.

Although I have shown and described a certain specific embodiment of the invention, I am fully aware that modifications thereof are possible. My invention, therefore, is not to be restricted except in so far as is necessitated by the prior art and by the scope of the appended claims.

Having thus described the invention what I claim as new and desire to secure by Letters Patent is:

1. A sheet positioning means for printing presses comprising a fixed support, a member having a longitudinal slot receiving the support, a pin supported on the member and a sleeve on the pin shiftable radially thereof.

2. A sheet positioning means for printing presses comprising a member adaptable for mounting on the feed board of a printing press for pivotal and shiftable movements, a pin on the member, and a sleeve on the pin movable in any direction in a plane transversely of and in normal relation to the pin.

3. A sheet positioning means for printing presses comprising a fixed support, an elongated plate having a longitudinal slot receiving the support, a pin supported on one end of the plate in normal relation thereto, and a sleeve supported on the pin and shiftable in a plane transversely thereof and normal thereto.

4. A sheet positioning means for printing presses comprising a vertical axially movable support, an elongated plate having a longitudinal slot receiving the support, a pin secured to the plate adjacent one end thereof in normal relation thereto, a sleeve on the pin shiftable in any direction in a plane normal to the pin and a head on the pin inhibiting axial movement of the sleeve.

5. A sheet positioning means for a printing press comprising an axially movable support, a plate having a longitudinal slot receiving the support, a pin secured to the plate adjacent one end thereof and in normal relation thereto, a washer slipped on the pin and secured to the plate, a sleeve on the pin of smaller diameter than the washer shiftable in any direction in a plane normal to the pin, a head on the pin inhibiting axial movement of the sleeve, and means on the vertically movable support for clamping the plate.
